Des. 198,525
Patented June 30, 1964

198,525

DRIVE-THROUGH RESTAURANT BUILDING

Lowell A. Odell, Jr., 806 W. 6th St., Atlantic, Iowa

Filed Mar. 25, 1964, Ser. No. 79,183

Term of patent 14 years

(Cl. D13—1)

Fig. 1

Fig. 2

Fig. 3

Fig. 4

FIG. 1 is a front perspective view of a drive-through restaurant building, showing my new design;

FIG. 2 is a front elevational view thereof;

FIG. 3 is a side elevational view thereof, both sides being identical in appearance; and

FIG. 4 is a rear elevational view thereof.

The words shown in broken lines in FIG. 2 are disclosed for illustrative purposes only.

I claim:

The ornamental design for a drive-through restaurant building, substantially as shown and described.
